UNITED STATES PATENT OFFICE.

HENRY V. RAU, OF BROOKLYN, NEW YORK, ASSIGNOR TO EDWIN B. STIMPSON COMPANY, OF BROOKLYN, NEW YORK, A CORPORATION OF NEW YORK.

MARKING BUTTON.

1,407,085.

Specification of Letters Patent. Patented Feb. 21, 1922.

Application filed April 26, 1918. Serial No. 230,945.

To all whom it may concern:

Be it known that I, HENRY V. RAU, a citizen of the United States, residing at Brooklyn, in the county of Kings and State of New York, have invented certain new and useful Improvements in Marking Buttons, of which the following is a specification.

My invention relates generally to buttons and particularly to buttons of a type that is intended to bear indicating characters to be used in marking various materials.

Devices of this general nature are well known in the art and they have usually consisted of a tubular rivet formation, the stem of which was adapted to be fastened in the material to be marked and the flattened head of which had a sheet metal disc bearing the marking indicia applied thereto with the edge of the disc clinched over the edge of the flattened rivet head. This construction presented a number of serious disadvantages. One of these disadvantages consisted in the necessary use of metal for the face member bearing the indicating character in order to provide a sufficiently substantial construction to withstand the clinching operation by which the face member was attached to the flattened rivet head. This added greatly to the cost of the buttons, particularly when, as was usually the case, it was necessary to make use of the buttons on a very extensive scale. Another disadvantage of the construction described resided in the tendency which the unsupported central portion of the face member had to collapse into the underlying open end of the tubular stem to such an extent as to affect the legibility of the indicating character and render it difficult to read. On the other hand, when the face member has retained its position and has not been bent into the underlying opening, the exposed position of the face member has rendered the indicia carried by it peculiarly susceptible to damage by abrasion or other injury occasioned by mechanical contact with surrounding objects.

The principal object of the present invention is to provide a marking button of the general type indicated in which the disadvantages referred to as existing in prior devices are overcome.

With this and other objects in view, one feature of the invention consists in the provision of a button in which the upstanding flange of the cup-shaped body member is

clinched over the edge of the face member, thereby providing for the use of comparatively cheap material such as paper or celluloid for the face member.

Another feature of the invention consists in upsetting the flange of the body member over the edge of the face member in such a way that a raised formation is presented around the edge of the face member, whereby the surface of the face member is afforded protection against injury.

Still another feature of the invention resides in the interposing of a rigid supporting member between the indicia carrying face member and the end of the tubular stem to prevent the collapse of the face member into the adjacent underlying core of the stem.

Other features of the invention will be hereinafter described.

In the drawings,

Figure 1 is a plan view of a button embodying a preferred form of the invention.

Figure 2 is a sectional view of the button shown in Figure 1.

Figure 3 is a plan view of a character bearing member forming part of the device.

Figure 4 is a plan view of a bridging or supporting member forming part of the device.

Figure 5 is a plan view of the main body portion of the button before the different parts are assembled.

Figure 6 is a sectional view of a modified form of button.

In Figure 2 of the drawing there is shown in section a view of a preferred form of the invention in which a main body member is indicated at 1 with the upper part of the rim of its cup-shaped top upset onto the edge of the face member 2 bearing the character 3. The body member 1 is preferably formed of sheet metal and has for a stem a tubular rivet formation as indicated at 5, the tubular stem 5 being adapted to be passed through any desired sheet material 6 to which it is desired to apply the marking button and to have its end clinched or upset to hold the stem and the button in place, in an obvious manner.

It is the practise to make marking buttons of this general nature in comparatively small sizes so that the area of the central portion of the face member overlying the adjacent open end of the tubular stem may

comprise a relatively large proportion of the total area of the face member and for that reason renders the indicating character on the face member very difficult to read when, 5 for any reason, the central portion of the face member has collapsed into the underlying open end of the tubular stem. With a view to correcting this defect, I have adopted the expedient of interposing the 10 bridging member shown in plan view in Figure 4 of the drawing between the face member 2 and the bottom of the cup-shaped head of the body member 1 and have thus effectually prevented any possibility of a 15 collapse of the face member into the core in the stem. The core bridging member 4 may be made of any suitable sheet material having a sufficient degree of thinness with the necessary rigidity to reinforce the 20 face member and prevent its collapse into the hollow stem.

It will be seen that the raised portion of the flange 8 which is formed not only obviates the necessity of using a metallic material for the face member 2 and thus provides for the use of inexpensive material such as paper, but that the raised formation presented by the flange serves to protect the 25 surface of the face member 2 and the character 3 inscribed thereon from defacement of any sort. The effectiveness of this protection is enhanced by the relatively small diameter of the buttons as they are used in actual practise.

35 As a further means of protection against injury of the face member 4, a special cover member 7 made of thin and transparent material such as sheet celluloid, may be added as in Figure 6 where conditions so warrant.

40 It will be evident from the construction described that a marking button has been produced that is free from the defects present in prior devices, and that is inexpensive to manufacture and substantial and durable 45 in character. The button as thus produced is easily attached to the desired material by simply pressing the tubular rivet forming

the stem 5 through the material, or through a hole previously formed therein, and clinching the end of the stem on the under- 50 side of the material.

Having thus described my invention, what I claim and desire to secure by Letters Patent of the United States is:

1. A button comprising: a disc-shaped 55 face member, a body member having an edge thereof upset over the edge of said face member to form a raised flange around said edge, a tubular stem on said body member having an open end of the core therein in 60 contiguous relation to the underside of the central portion of the face member, and a bridging member formed of sheet material interposed between said face member and the core in said tubular stem. 65

2. A marking button comprising: an indicia bearing face member, a cup-shaped body member serving as a seat for said face member and having the rim thereof clinched over the edge of said face member to form a 70 raised protecting flange thereon, a tubular stem on said body member, and a sheet metal bridging member for preventing the collapse of said face member into the core of 75 said stem, said bridging member having supporting engagement with said face member along two diameters of said face member substantially at right angles to each other.

3. A marking button comprising: an indicia bearing face member, a cup-shaped body member serving as a seat for said face member and having the rim thereof clinched over the edge of said face member, a tubular stem on said body member, and a bridging member formed of rigid sheet material 85 interposed between said face member and the core of said tubular stem and extending across the seat formed by said cup-shaped member. 90

Signed at Brooklyn, in the county of Kings, and State of New York, this 20th day of April, 1918.

HENRY V. RAU.
